(57) CLAIM

The ornamental design for an atomizer, as shown and described.

DESCRIPTION

FIG. 1 is a top perspective view of the atomizer of the present invention, the middle portion being transparent; FIG. 2 is a bottom perspective view thereof;

FIG. 3 is a first side view thereof;

FIG. 4 is a second side view thereof;

FIG. 5 is a third side view thereof;

FIG. 6 is a fourth side view thereof;

FIG. 7 top plan view thereof; and,

FIG. 8 is a bottom plan view thereof.

The broken lines in the drawings depict portions of the atomizer that form no part of the claimed design.
